Inventor

Stanislaw Michalak

UNITED STATES PATENT OFFICE.

STANISLAW MICHALAK, OF TOLEDO, OHIO.

SPARK ARRESTER.

Application filed September 19, 1924. Serial No. 738,631.

To all whom it may concern:

Be it known that I, STANISLAW MICHALAK, a citizen of the United States, residing at Toledo, in the county of Lucas and State of Ohio, have invented new and useful Improvements in Spark Arresters, of which the following is a specification.

My invention relates to spark arresters especially adapted for chimneys and the like.

An object of the invention is to provide a device of this character which may be attached to a chimney and which will prevent the discharge of hot sparks and yet not interfere with the discharge of smoke.

A further object of the invention is to provide an extension for chimneys having a baffle plate for deflecting the sparks and branch passages encircling the baffle plate through which the smoke is conducted.

Another object of the invention is to provide a device of the above-mentioned character which is simple and durable in construction, reliable and efficient in use and inexpensive to manufacture.

Other objects and advantages of the invention will be apparent during the course of the following description.

In the accompanying drawing forming a part of this specification and in which like numerals are employed to designate like parts throughout the same,

Fig. 1, is a side elevation of the attachment,

Fig. 2, is a longitudinal sectional view of the same,

Fig. 3, is a top view, and,

Fig. 4, is a cross section on lines 4—4 of Fig. 2.

In the drawing, wherein for the purpose of illustration I have shown a preferred embodiment of my invention, the numeral 5 denotes a tubular pipe provided at its lower end with a square base 6 having depending flanges 7 adapted to be fitted over the top of a chimney (not shown) and secured thereto by set screws 8. Mounted within the pipe adjacent the upper end thereof is an inverted truncated cone shaped baffle plate 9. The smoke and sparks emitted from the chimney in passing through the pipe will strike the baffle plate 9, causing the sparks to be de-

flected down into the chimney and the smoke diverted into the arc shaped tubular branch passages 10. These passages will vary in number according to the size of the chimney and are disposed longitudinally of the pipe in spaced relation. The lower ends of the passages are connected to the pipe below the baffle plate, as at 11, and the upper ends connected to the pipe above the baffle plate, as at 12, so the smoke will be conducted around the baffle plate and discharged out of the upper end of the pipe. The upper end of the pipe is flared outwardly, as at 13, and a conical shaped cap 14 is supported above the pipe in spaced relation by the vertical brackets 15 protecting the chimney from rain and dirt. The base of the cap extends beyond the edge of the pipe being on a horizontal plane therewith, so the smoke and cinders will be deflected downwardly. Should dirt or cinders accumulate on the baffle plate, it will be discharged through the opening 16 in the baffle plate.

Thus it is seen, that in use this attachment will prevent the discharge of hot sparks from the chimney, thereby eliminating the danger of fire resulting from flying sparks and yet will not interfere with the draft of the chimney or discharge of the smoke.

It is to be understood that the form of my invention herewith shown and described is to be taken as a preferred example of the same and that certain changes in the shape, size and arrangement of parts may be resorted to without departing from the spirit of the invention or the scope of the subjoined claims.

Having thus described my invention I claim:

1. A device of the character described including a pipe, an inverted truncated cone shaped baffle plate mounted within said pipe, and a plurality of branch passages having one end connected to said pipe below said baffle plate and their opposite ends connected to said pipe above said baffle plate.

2. A device of the character described including a pipe, an inverted truncated cone shaped baffle plate mounted within said pipe, a plurality of arc shaped branch pas-

sages having connection with said pipe above and below said baffle plate, and means for connecting said pipe to a chimney.

3. A device of the character described including a pipe, an inverted truncated cone shaped baffle plate mounted within said pipe, and a plurality of arc shaped branch

passages disposed longitudinally of said pipe having connection therewith above and below said baffle plate.

In testimony whereof I affix my signature.

STANISLAW MICHALAK.
